UNITED STATES PATENT OFFICE.

WILBUR L. SHEPARD, OF HARTFORD, CONNECTICUT.

DESIGN FOR A LAMP-BODY.

SPECIFICATION forming part of Design No. 16,797, dated July 13, 1886.

Application filed April 29, 1886. Serial No. 200,632. Term of patent 7 years.

To all whom it may concern:

Be it known that I, WILBUR L. SHEPARD, of Hartford, Connecticut, have invented and produced a new, useful, and original Shape or Configuration of a Lamp, of which the following description and claim constitute the specification, and which is shown in the accompanying sheet of drawings.

My design relates to the reservoir.

10 Figure 1 is a side view, and Fig. 2 is a central vertical section, of a lamp reservoir showing my design.

15 A is the body of the reservoir. It has the form of a truncated hemisphere with its equatorial diameter upward.

C is the top of the reservoir, provided with a central opening for the reception of any suitable burner, and having its radial sections

in the form of a compound curve, so as to produce the outer annular concavity shown in 20 Fig. 2.

The handle is not essential to the design, and may be omitted or retained, as preferred.

I claim as my invention—

25 A design for a lamp-reservoir composed of the body A, which is in the form of a truncated hemisphere with its equatorial diameter upward, and of the top C, provided with a central opening, and having its radial sections in the form of a compound curve, all substantially as described in the description and shown in the drawings.

WILBUR L. SHEPARD.
